UNITED STATES PATENT OFFICE.

RALPH E. HURST, OF WELLINGTON, KANSAS.

PUMP.

1,137,211.

Specification of Letters Patent. Patented Apr. 27, 1915.

Application filed October 16, 1913. Serial No. 795,503.

To all whom it may concern:

Be it known that I, RALPH E. HURST, a citizen of the United States, residing at Wellington, in the county of Sumner and State of Kansas, have invented certain new and useful Improvements in Pumps; and I do declare the following to be a full, clear, and exact description of the invention, such as will enable others skilled in the art to which it appertains to make and use the same.

This invention relates to pumps, and more especially to those having multiple cylinders and multiple pistons arranged in tandem; and the object of the same is to provide improved means for guiding the piston rods and the cross heads with which the pitmen rods are connected.

This and other objects are carried out by constructing the machine in the manner hereinafter more fully described and claimed and as shown in the drawings wherein—

Figure 1 is a general vertical sectional view of this entire pump and the actuating mechanism therefor, and Fig. 2 is a side elevation of the same. Fig. 3 is an enlarged vertical sectional view of the pump alone, and Fig. 4 is a cross section on the line 4—4 of Fig. 2.

Referring to the drawings by reference numerals 1 designates the casing of each of several cylinders (three being shown in the drawings although there may be a greater number) which are preferably alike with the exceptions that will be noted. This casing may be a rough casting having an axial bore 2 enlarged at one end as at 3—preferably the lower end—and cored with two by-pass ports or passages 4 connecting the ends of the casing beyond the extremities of the bore. The extremities of the casing are by preference provided with radial flanges 5 by means of which each casing is connected by bolts 6 with the casing adjacent. The bottom of the lowermost casing is closed by a plate 7 having an inlet port 8. The top of the uppermost casing is closed by a plate 9 having an outlet port 10 and at its center a large hole 11 around which the walls of this plate are thickened so as to produce a cavity for the reception of packing 12—the packing being held in place by a gland 13 which is secured to the plate by bolts or screws 14. The upper or outlet end of each by-pass is closed by a valve

15 opening upwardly, and the detailed construction of this valve is not essential. These by-pass passages augment the operation of my pump, in as much as they allow a portion of the water compressed by the moving pistons to be forced through said by-pass passages, into the chamber above each of the respective pistons, which tends to overcome the difference in movement between the pistons, and consequently cause the pump to operate a good deal smoother than it would without the use of said passages.

The cylinder for each casing may be of different metal, and its bore is nicely turned for the reception of the piston yet to be described. This cylinder has a truly cylindrical body 16 whose length is a little greater than the bore 2 of the casing 1, whose wall is rather thin, whose external diameter is the same as the internal diameter of said bore and therefore less than the internal diameter of the bore where it is enlarged as at 3, and whose body has around it a radially projecting flange 17 to rest against the shoulder where the bore 2 is enlarged as at 3, against which shoulder it is held by any suitable means such as the screws 18. By this means the entire cylinder or lining is removable from the bore of the casing so that it may be replaced when it becomes worn.

The piston fits slidably within the bore of the cylinder or liner and may be of any suitable material. Its body 19 has some considerable thickness and a surrounding groove for packing 20, and said body is provided through it with a plurality of ports 21 closed by valves 22 whose detailed construction is not important to this invention. These valves close downward as do the other valves 15 above referred to.

The numeral 23 designates a plate secured to the bottom of the body 19 by screws 24 or otherwise and having ports 25 adapted to register with those in the body, and the edge of this plate closes the groove which contains the packing 20 and fits slidably within the bore of the liner. The plates and pistons are all alike excepting for the difference in the size of their axial holes. The means for driving these pistons constitutes one of the features of this invention. Secured in the axial hole 26 of the uppermost member is the lower end of a tubular piston rod 27 which projects slid-

ably through the packing 12 above referred to, and the upper end of this rod is connected with a cross head 28 by suitable means as by screwing into the same as shown. By preference said cross head is provided in its upper face with a cavity for packing 29, and the latter is held in place by a gland 30 which is fastened to the cross head by any suitable means such as screws 31. In similar manner the piston rod 32 is a tube of smaller size whose lower end is connected with the piston of the intermediate cylinder, whose body passes slidably through the bore of the tubular piston rod 27, and whose upper end is connected with the second cross head 33—preferably by the same type of connection as just described. In similar manner the third or lowermost piston is carried by a solid piston rod 34 which preferably passes through the same and receives a nut 35 at its lower end, the body of this rod passing through the smaller tubular pitman rod 32 and projecting at its upper end and connecting with the third or upper cross head 36.

The guides for the several cross heads are of peculiar construction and form an essential feature of the present invention. That is to say the first—which is the lowest and longest—cross head 28 extends through the upright slots in four guides 40, 41, 42, and 43, the larger tubular piston rod 27 being connected with the center of the cross head and its ends being suitably connected by pitman rods 44 and 45 with two cranks 46 and 47 on a power shaft 48. The next shorter cross head 33 extends through the two innermost guides 41 and 42, the smaller tubular piston rod 32 being attached to the center of this cross head, and its extremities being connected by pitman rods 49 and 50 with two other cranks 51 and 52 on said shaft 48, these cranks being disposed 120° from the first-mentioned cranks 46 and 47. The third, which is the shortest and highest, cross head 36 has its extremities sliding between the guides 41 and 42 but not projecting beyond them where they might interfere with the pitman rods 49 and 50. To the center of this cross head is connected the upper end of the solid piston rod 34, and is pivoted a single pitman rod 53 which connects with another crank 54 on the power shaft 48, this crank being disposed 120° from either of the other pairs of cranks so that the disposition of the three sets of cranks is one-third away from each other as shown.

The action of this pump is as follows: The inlet 8 being connected with a source of supply or submerged in the water, and the outlet 10 being connected with the nozzle through which the delivery of the water is desired; when rotary motion is imparted to the power shaft 48 the several pitman rods

cause the reciprocation of the various cross heads, and these through the piston rods cause the reciprocation of the various pistons within their cylinders. On the ascent of any piston head the water above it will be lifted through its cylinder or liner and forced upward through the ports in the cylinder head above and through valves 15, located at the upper extremity of the by-passages 4, and into the space intervening between each of the casings as clearly shown in Fig. 3 if the latter is descending or forced into the by-pass passages 4 in that casing if its piston is ascending. On the descent of any piston head its valves open and water is admitted through the ports 21. Valves 15 prevent the setting back or downward flow of water through the by-passages 4. By preference the various perforations 21 in the several piston heads are arranged in alinement with each other so that there is a straight upward course for the water from the inlet to the outlet end of the entire pump. Where the solid piston rod 34 slides within the inner tubular rod 32 and the latter within the outer tubular rod 27, little if any lubrication is necessary because at each stroke of the pump these various rods are bathed in water and friction and heat will therefore not occur, any more than it would where the packing 20 slides within the liner. Where the various cross heads slide within their guides, lubrication may be necessary as common in machines of this class. Access to the interior of any casing is readily had by removing the bolts 6 connecting its flanges 5 with the next casings or with the end plates 7 or 9, and removing this member entirely. I would suggest that a complete pump might have four such members, and when one becomes defective or worn it can be bodily removed and replaced so that the action of the pump may be continued uninterruptedly while the defective member is repaired. I apprehend, however, that the most wear will occur within the liner which in time must be removed to replace it or to replace the packing 20. This is accomplished by removing this member, then withdrawing the bolts or screws 18 which hold the liner in place, and pulling the liner out of the bore of the casing 1—replacing the same with a new liner, and then replacing the member. I do not wish to be limited to the sizes or materials of parts, and changes in details may be made without departing from the principle of the invention.

What is claimed as new is:

1. In a pump, a casing having a tubular bore and provided with a series of by-pass passages, each having their extremities in communication therewith, valves at the upper extremities of said by-pass passages, and a plurality of valved pistons concentrically mounted and movable relatively within said

bore and operating in conjunction with said by-pass passages substantially as and for the purposes set forth.

2. In a pump, a casing having a tubular bore and provided with a series of by-pass passages extending longitudinally of the bore, the latter having their extremities communicating with said bore, a valve at the upper extremity of each of said passages and a plurality of valved pistons concentrically mounted and movable relatively within said bore and operating in conjunction with said passages, substantially as and for the purpose as set forth.
- 15 3. In a pump, a casing having a tubular bore, and provided with a plurality of valved pistons, concentrically mounted and movable relatively within the latter, a plurality of arcuate shaped by-pass passages extending longitudinally of the bore and having their extremities communicating with the latter above and below the pistons therein, valves operatively disposed at the upper extremities of said passages, said valved pistons and by-passages cooperating substantially as and for the purpose set forth.
- 20 4. In a pump, a casing having a tubular bore and provided with a series of liners arranged in spaced relationship within the said bore, a series of arcuate shaped by-pass passages extending longitudinally of the bore and having their extremities communicating with the latter above and below each of said liners, valves operatively disposed at the upper extremities of said by-pass passages and a piston disposed in each of said liners, said pistons being concentrically
- 25
- 30
- 35

mounted and movable relatively to coöperate with said by-pass passages, substantially as and for the purposes set forth.

5. In a multi-cylinder pump, a plurality of inter-connected casings each having a tubular bore provided with a liner, each casing having a pair of by-pass passages extending longitudinally thereof whose extremities communicate with its bore, above and below the line therein, valves disposed at the upper extremities of said by-pass passages, and a reciprocating valved piston operatively disposed in each of said liners, to coöperate with said by-pass passages substantially as and for the purpose set forth.

6. In a multiple cylinder pump, a plurality of casings each having a tubular bore and also provided with by-pass passages around the bore affording communication between the end portions of the casing, annular flanges formed on the extremities of said casings, the flanges of the respective casings being secured together to connect said casings in tandem, a bottom plate removably secured to the flange at the lower end of the lowermost casing and having an inlet port therein, a top plate removably secured to the upper flange of the uppermost casing and having an outlet port therein, and pistons mounted for reciprocation respectively in the bores of said casings.

In testimony whereof I have hereunto set my hand in presence of two subscribing witnesses.

RALPH E. HURST.
